UNITED STATES PATENT OFFICE.

JAMES E. McWHORTER, OF COLORADO SPRINGS, COLORADO.

TENT-SECURING DEVICE.

Application filed February 28, 1923. Serial No. 621,858.

To all whom it may concern:

Be it known that I, JAMES EDWARD McWHORTER, a citizen of the United States, residing at Colorado Springs, in the county 5 of El Paso and State of Colorado, have invented new and useful Improvements in Tent-Securing Devices, of which the following is a specification.

This invention relates to an attachment 10 for a tent, the general object of the invention being to provide means for holding the lower part of the tent wall in position and also to hold the anchor rope taut.

Another object of the invention is to provide means for holding the anchor rope engaging member in any desired position.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is an end view of part of a 30 tent showing the invention in use.

Figure 2 is a side view of Figure 1.

Figure 3 is an enlarged side view of the device itself.

Figure 4 is a section on line 4—4 of Figure 3.

Figure 5 is a section on line 5—5 of Figure 3.

In these views 1 indicates the body of the device which is preferably formed of 40 strap iron and is formed with a loop 2 at its upper end, a point 3 at its lower end and a projection 4 an appreciable distance above the point, said projection being provided with a brace 5. A brace 6 is placed 45 in the loop and holes 7 are formed in the top of the loop, the brace 6, the lower part of the loop, the projection 4 and its brace 5 for slidably receiving a rod 8 which has its upper end forked, as at 9. A trigger plate 50 10 is hingedly supported in the loop above the brace 6, preferably by means of a projection 11 thereon passing loosely through a hole 12 formed in the rear part of the

loop, said plate being limited in its downward swinging movement by the upper edge 55 of the inner end of the brace 6. This plate is provided with a hole 13 for receiving the rod 8, this hole being made to snugly receive the rod so that when the plate is in its lowered position, the hole being inclined, its walls will engage the rod and thus hold it in raised position through friction. When the rod is pushed upwardly the plate will move upwardly with it to a sufficient extent to permit free movement of the rod through 65 the hole therein.

In using the invention the pointed end of the device is placed in engagement with one of the loops 14 at the bottom of the tent wall, as shown in Figures 1 and 2, and 70 then the pointed end is forced into the ground by means of a foot pressing upon the projection 4 or by striking said projection with an axe or the like. The rod 8 is then raised to place its forked upper end 75 in engagement with one of the anchor ropes 15 of the tent to tighten the same.

From the foregoing it will be seen that the device can be easily and quickly placed in position to hold the bottom of the tent 80 wall in place and to tighten the anchor ropes of the tent. The device will have long life and as it is of light weight and of simple construction it can be manufactured to sell at low cost and it will not take up much 85 room when not in use.

It is thought from the foregoing description that the advantages and novel features of my invention will be readily apparent.

I desire it to be understood that I may 90 make changes in the construction and in the combination and arrangement of the several parts, provided that such changes fall within the scope of the appended claims.

What I claim is:—

1. A device of the class described comprising a body part having a pointed end, projections on the body part, one of which serves as means for forcing the pointed end into the ground, said projections having 100 holes therein, a rod adapted to pass through said holes, a plate hingedly connected with the body part above one of the projections and having a hole therein for receiving the rod.

2. A device of the class described com-

prising a body part having a loop at its upper end and a point at its lower end, a projection adjacent the lower end having a hole therein, a brace in the loop having a hole therein, the top and bottom of the loop having holes therein, a rod adapted to pass through the holes and having a forked up-

per end and a plate having a hole therein and hingedly connected with the body part above the brace and acting to prevent downward movement of the rod. 10

In testimony whereof I affix my signature.

JAMES E. McWHORTER.
